SCANNING AND RECORDING DEVICE FOR ELECTROSTATIC RECORDING

BACKGROUND OF THE INVENTION

1. Field of the Invention

This invention relates to a scanning and recording device for electrostatic recording in a facsimile system, particularly to such a device utilizing a multistylus electrode.

2. Description of the Prior Art

Generally speaking, the recording process with an electrostatic recording system comprises the steps of, causing a recording stylus to contact the surface of an electrostatic recording paper which is coated with an insulating resin or the like, applying a signal voltage of several hundred volts to said recording stylus thereby to produce a latent image of electrification corresponding to said signal voltage on said insulating layer of resin, and developing and fixing said latent image to obtain a visible recording. Such a process with which an electrostatic latent image is directly produced by electrical means, requires a comparatively high voltage but little recording current. Therefore, such a recording system is economical in power consumption, suitable for high-speed recording and produces a distinct record of good contrast on white paper.

In one conventional electrostatic recording system, it is a common practice to adopt a planar scanning system, as it is convenient to continuously advance the recording paper for the developing and fixing process after the electrostatic latent image has been produced. Typical examples of the conventional electrostatic recording systems will be described hereunder.

Endless belt-type scanner comprises a plurality of metallic styluses planted at uniform spaces on an endless belt extended between a pair of pulleys, the recording being performed by imposing the signal voltage on said styluses which scan a dielectric recording paper in contact with said paper. This system is not advantageous in regard to the following points that it is not suitable for high-speed scanning, that the reproduced picture is deteriorated by the frictional electrification as the styluses are run in contact with the recording paper, and that it is short in service life because of damage to the belt and other components.

Other conventional electrostatic recording systems include planar scanning systems in which the ends in one side of a number of insulated conductors are aligned uniformly to form a multistylus electrostatic recording head and the other ends are connected to a signal distributor which comprises terminals disposed in a circle and a rotating wiper, and with which the electrostatic recording is performed on a recording paper which moves adjacent to the recording head, the image signal introduced through said signal distributor being led to said styluses in the recording head. A great disadvantage of this system is that it is not simple nor easy to construct.

A further example of the conventional scanning systems is the electrostatic recording tube which is a cathode ray tube whose faceplate is provided with an array of a number of styluses penetrating therethrough, said array of styluses being scanned at their inner ends with the electron beam whose intensity varies in correspondence with the image signal voltage, and thus the electrostatic recording being made on a recording paper which is passed adjacent to the faceplate. Though this known system is suitable for high-speed scanning, it has a great disadvantage in regard to the following points that such an electrostatic recording tube is difficult to fabricate and very high in cost.

SUMMARY OF THE INVENTION

An object of this invention is to provide a scanning and recording device for electrostatic recording comprising two electroconductive sheets attached to both surfaces of a dielectric sheet, one of said two electroconductive sheets being photoetched to form a multistylus and the other sheet being used as a ground electrode, an electrostatic recording head

formed in one of the end portions of said sandwiched sheets, and a cylindrical scanning portion formed in the other end portion of said sandwiched sheets.

Another object of this invention is to provide a scanning and recording device for electrostatic recording wherein said electrostatic recording head in said one end is inclined against the recording paper in order to increase the area of the end of a stylus in contact with the recording paper.

This invention has eliminated the previously mentioned disadvantages of the conventional systems, and has made it possible to effect a high-speed scanning with a simple structure. Further, according to this invention, an increased density of recording is obtained, as the shape of an elementary dot of record which was conventionally a circle is made an ellipse thereby to fill more area in the space between subscannings or two rows of main scanning.

BRIEF DESCRIPTION OF THE DRAWING

- 20 FIG. 1 is an isometric view of sandwiched sheets used in this invention;
 FIG. 2 is a side view of the sandwiched sheets shown in FIG. 1;
 FIG. 3 is an isometric view of an embodiment of the scanning and recording device of this invention;
 FIG. 4 shows an equivalent circuit of the capacitance between conductors of the sandwiched sheets;
 FIG. 5 is a schematic diagram illustrating a conventional scanning system;
 30 FIG. 6 is an example of a record made by the conventional system shown in FIG. 5;
 FIG. 7 is a schematic diagram illustrating the scanning and recording device of this invention in use;
 FIG. 8 is an example of a record made by the device shown in FIG. 7;
 FIG. 9a is an isometric view of another embodiment of the scanning and recording device of this invention; and
 FIG. 9b is an enlarged view of a portion of the device shown in FIG. 9a.

DESCRIPTION OF THE PREFERRED EMBODIMENTS

A scanning and recording device of this invention comprises a sandwiched formation including two electroconductive sheets attached to both surfaces of a dielectric sheet, one of the electroconductive sheets being photoetched to form a multistylus and the other of the electroconductive sheets being used as a ground electrode.

Referring to FIGS. 1 and 2, the multistylus 2 is seen to be provided on one surface of the dielectric sheet 1 and the ground electrode 3 on the other surface. One end portion of the above-described sandwiched sheets is formed into a cylinder to be used as a part of the scanner or distributor, while the other end portion is maintained flat and straight and is solidified with a synthetic resin or the like to be formed into a recording head 4. In this embodiment, the above-mentioned cylindrical portion is formed with the multistyluses 2 outside and the ground electrode 3 inside. As shown in FIG. 3, a pair of brushes 6 and 7 are provided in contact with said cylindrical portion and a high voltage corresponding to image signal is applied to said brush 6 while said brush is rotated around the cylindrical portion. Thus, on the other end of the device, an electrostatic image is obtained through the recording head 4 on a recording paper 5 which is moved in the direction perpendicular to the lengthwise direction of the recording head. The thus obtained electrostatic latent image is turned to a visible image through development with a toner.

In FIG. 4 which shows an equivalent circuit of the capacitance between conductors, each conductor $2_1, 2_2, 2_3, \dots$ leading to each stylus is seen on one surface of the dielectric sheet 1. In operation, when a signal voltage is applied to a stylus or conductor through the brush 6, a voltage is induced in the adjacent conductors owing to the static capacitances $C_1, C_2, C_3, \dots$ between the conductors. The charge distribution

due to the leakage of the image signal voltage to adjacent conductors remarkably lowers the resolution of the picture in the direction of the main scanning. To prevent the above-mentioned deterioration of the resolution, the around electrode 3 is provided opposite to the conductors of the multistylus. Thus, the effects of the static capacitances $C_1, C_2, \dots$ between adjacent conductors are reduced by the capacitances $C', C'', C''', \dots$ between respective conductors and the ground. For example, assuming that a signal voltage V is applied to the stylus or conductor 2_2 through the brush 6, voltage V_1 induced in the adjacent conductor 2_1 or 2_3 is divided between C_1 and C' , or between C_2 and C''' as shown by the following formula:

$$V_1 = \frac{C_1}{C_1 + C'} V$$

Brush 7 shown in FIG. 3 is grounded and is rotated with the brush 6 but a bit behind it thereby to eliminate the residual electricity owing to the capacitances $C', C'', C''', \dots$ indicated in FIG. 4.

Next, relative position of the stylus on the recording paper and the quality of the resultant record will be explained with reference to FIGS. 5 to 8. In FIG. 5 which shows a conventional system, reference numeral 11 indicates a stylus or conductor, 12 dielectric sheets, 13 electrostatic recording paper, 14 a cushion for urging the recording paper 13 against the stylus 11, 15 a scanner, and 16 an amplifier. In this arrangement, if a voltage related to the input signal is applied to the conductor or stylus 11, the recording paper is electrified at the spot where said stylus is in contact with the paper, thus a latent image being made on the paper. This latent image is turned to a visible image as shown in FIG. 6 through the development. In FIG. 6, a visible image 18 is seen on the recording paper 13. Electrification of the recording paper and amount of the toner deposited on the latent image vary depending on characteristics of the recording paper and the developing agent, and the density of the record is limited. Assuming that the space between adjacent styluses is a and the space of the sub-scanning is b as shown in FIG. 6, it is required for obtaining a satisfactory apparent density to reduce the spaces a and b as much as possible. In a high-speed recording with low density scanning, the space b is inevitably coarse resulting in low apparent density. According to this invention, the recording head 22 is positioned in such a manner that the multistylus 21 is inclined against the recording paper 23 at an angle θ as shown in FIG. 7. In FIG. 7, reference numeral 24 indicates a cushion for urging the recording paper 23 against the stylus 21, numeral 25 the ground electrode, 26 a scanner, and 27 an amplifier. In this arrangement, if a voltage related to the input signal is applied to the stylus 21, the recording paper is electrified at the spot where said stylus is in contact with the paper, thus a latent image being made on the paper. This latent image is turned to a visible image as shown in FIG. 8 through the development. In FIG. 8, a visible image 28 is seen on the recording paper 23. An elementary dot of the image has the shape of an ellipse in FIG. 8, whereas it is a circle in FIG. 6. The length of the long axis of the ellipse is determined by the angle θ , and so is the space C' between adjacent dots in the direction of the subscanning. Effects of this arrangement will be further explained hereunder.

Assuming that the multistylus included m/mm elementary styluses, the diameter of each stylus being γ mm and that the

rate of subscanning is F -lines/mm, the conventional system as shown in FIG. 5 will produce a record in which the center distance b between adjacent dots in the direction of sub-scanning is $1/F$ and the space between dots in the same direction is $1/F - \gamma$. According to this invention, each of the elementary dots of the record assumes the shape of an ellipse as shown in FIG. 8 owing to the inclination of the stylus by the angle θ , thus the length of the long axis of the ellipse being $\gamma/\cos \theta$ and the space c' between adjacent lines being $1/F - \gamma/\cos \theta$. As $\gamma/\cos \theta$ is larger than γ in the range of $0 < \theta < 90^\circ$, the space C' in FIG. 8 is smaller than the space C in FIG. 6. Thus, the apparent density of the image in the direction of the sub-scanning is improved.

FIGS. 9a and 9b show another embodiment of the scanning and recording device of this invention. In this embodiment, the cylindrical end portion of the device is formed with the multistylus 102 inside and the ground electrode 103 outside, contrary to the embodiment shown in FIG. 3. The dielectric sheet is indicated by numeral 101 in the FIG. Scanning is performed by applying a high voltage corresponding to an image signal to the brush 106 while said brush is rotated inside the cylindrical portion. Thus, on the other end of the device, an electrostatic latent image is obtained through the recording head 104 on a recording paper which is moved in the direction of the subscanning. Another brush 107 which is grounded is rotated with the brush 106 but a bit behind it to eliminate the residual electricity. In this embodiment too, the feature of the inclined stylus as shown in FIG. 7 may be included in order to improve the recording density.

We claim:

1. A scanning and recording device for electrostatic recording, comprising a pair of electroconductive sheets each of which is substantially planar, a dielectric sheet disposed between and substantially coextensive with said electroconductive sheets to form a sandwich therewith, one of said electroconductive sheets being photoetched to provide raised portions comprising styluses the other of said electroconductive sheets being adapted to serve as a ground electrode, one end of said sandwich being formed in the shape of a cylinder and adapted to serve as a scanner, the other end of said sandwich presenting a substantially planar recording head, and the said dielectric sheet being of substantial thickness relative to the distances between said styluses so as to thereby reduce the static capacitance between said styluses and thus improve resolution of the recorded picture.
2. A scanning and recording device as defined in claim 1, wherein said styluses are inclined against the recording paper at a certain angle.
3. A scanning and recording device as defined in claim 1, wherein said cylindrical portion is formed with said styluses on the outside of the cylinder.
4. A scanning and recording device as defined in claim 3, wherein said styluses are inclined against the recording paper at a certain angle.
5. A scanning and recording device as defined in claim 1, wherein said cylindrical portion is formed with said styluses on the inside of the cylinder.
6. A scanning and recording device as defined in claim 5, wherein said styluses are inclined against the recording paper at a certain angle.
